UNITED STATES PATENT OFFICE.

OMAR G. FULLER, OF SAGINAW, MICHIGAN.

PROCESS OF PRODUCING DISPLAY FORMS.

Application filed May 8, 1925. Serial No. 29,182.

This invention deals with a certain new and useful improvement relating to the reproduction of forms usually employed in connection with the display of wearing apparel. These forms are quite extensively used by merchants handling apparel either in the form of skirts, waists, suits or in fact any garment either for male or female use.

Heretofore these forms have been made up from a plastic composition such as wax, papier-mâché or plaster Paris. It has been found that in practical use when the forms are composed of any of the materials just mentioned they have certain disadvantages. For instance, the wax composition is susceptible to easy breakage and then again it is not substantial enough to withstand any great amount of heat exposure. The papier-mâché form, while light enough in its character, usually presents a complete outline of the human figure in rough and unsightly formation. The plaster Paris formation has been found to be extremely heavy and liable to breakage.

To overcome all of the obstacles above raised, it has been my endeavor to produce a display form in which the reproduction of a human figure might be had, bringing out the fine detail body lines of the figure including the muscular and fine vein line effect throughout the formation. The display form, as produced by my process, also possesses the advantageous feature of being both light and durable. The rigidity of the produced form has been found by actual tests to withstand extreme violent usage. The finished article as produced by my process represents in its completed state an absolute reproduction of the object from which the master pattern is made.

To enable those skilled in this particular art to more readily understand my invention, I have in the attached sheets of drawing shown the manner in which the forms are produced and in the accompanying specification described the same to the best of my ability.

In the accompanying drawings, wherein similar letters of reference indicate like parts throughout the several views, Figure 1 is a perspective view of the master pattern which has been formed from a living object.

Fig. 2 is a perspective view showing the negative pattern applied over the positive pattern of Fig. 1. This view also illustrates the manner of sectionalizing the

negative pattern to facilitate its removal from the positive pattern.

Fig. 3 is a cross section taken through the body of the form on line 3—3 of Fig. 2.

Fig. 4 is a fragmentary sectional view taken through one of the legs of the display form and illustrating the manner of applying or lining the inner surface of the negative pattern with the pliable strips of material.

And Fig. 5 is a detail view illustrating the preferred type of joint between any movable member of the body.

Referring more in detail to the drawings, 70 10 designates the so called positive form which, in the present case, is composed of clay or the like, and represents an actual reproduction of a living person. In the formation of this master pattern all of the fine 75 body line effects should be carefully brought out.

After the reproduction of the master pattern, it is covered with a thin shell-like coating of plaster Paris or any other suitable material as shown in Fig. 2 and designated by the reference character 11. To prevent the positive adherence of this negative pattern to the positive pattern, the latter may first be coated with a film of oil or any other suitable preparation. This prevents the negative plaster Paris form from sticking or positively joining to the outer surface of the positive pattern. After this negative pattern has dried thoroughly, it is removed in 80 sections as suggested at 12—12—12 in Fig. 2.

This sectionalized negative pattern is then reassembled in a progressive manner, beginning at the head and assembling the sections downward therefrom. Before starting this 85 assembling operation, I have found it best to first cut away the sole portion of the foot section as illustrated at 13 in Fig. 4. This opening provides a suitable entrance into the curved portions of the foot so that the material which I will presently describe as the lining may be suitably and more efficiently placed therein.

This negative pattern when dried is in 100 condition to receive a lining material, which in the present case ultimately forms the outer surface of the display form. The manner in which this lining is formed on the surface of the negative pattern will now be described. Strips of pliable material such as dampened paper or the like from approximately an inch or two in width and

about fifteen to eighteen inches in length are placed in a vertical relation or as close thereto as possible with their edges slightly overlapping in the foot section 14. The upper ends of the strips extend slightly beyond the upper edge of this foot section 14 so they overlap the point of juncture between the foot section 14 and the lower leg section 15. These strips which are initially placed within the negative pattern are uncoated on their outer surface so as not to stick to the surface of the negative pattern. The inner surface of these strips are coated with any suitable form of adhesive. After the lower leg section has been attached to the foot section 14 the strips of pliable material are longitudinally placed in position within the section 15 so that they extend slightly beyond the section point indicated at 16-16. On these vertical strips of lining material are placed any number of diagonally arranged strips, these arranged strips being coated on both of their surfaces so as to effectively attach themselves to form the underlying or the overlying strips. I have found it advantageous to line the leg portions of the display form with six or seven plies of material so as to properly strengthen the complete figure. This built-up lining will form the body of the display form.

After the lining has been placed within the negative shell, the parts of the negative shell are immediately broken away and the complete form transferred to a drying room where it is allowed to remain until thoroughly dry. The exposed surface of this dry form is then sandpapered and covered with a hard finish which does not crack, chip or peel, rubbed down again until perfectly smooth and then tinted or colored to represent as closely as possible the human figure.

In order that the form shall be properly balanced, I have found it advisable to insert within the opening 13 at the foot section 14 a weighted body. This may be easily attached by securing a plate 17 carrying a leaded or iron insert 18 to the peripheral edges of the foot section 14.

I have also found it advisable to provide the joint connection between such parts of the body as the arms, legs, and waist, if necessary. This connection must be of a separable type to permit the proper dressing of the figure, more especially so in cases where the arms or legs of the display form are arranged in a crossed position. The preferred type of joint used in the present case is that disclosed in Fig 5 and as will be noted the same consists of two oppositely placed blocks 19-20 arranged respectively in the adjacent meeting faces of the body and arm of the display form. The block 19 carries a rotatable plate 21, the same being pivotally supported in its position by nut and bolt arrangement as designated at

22. This plate 21 is provided with slots as designated at 23-23 and the base plate 19 is recessed as at 24-24 for a purpose to be presently described. The base plate 20 is recessed as at 25 and fitting into this recess 25 is a friction disk 26. This friction disk is held within the recess 25 by the bolt 27, the latter being sprung urged by the coil spring 28 bearing at one end against the base plate 20 and at its opposite end against a nutted arrangement 29 carried by the free end of the bolt 27. The friction disk also carries two headed stud members 30-30 which are fashioned to engage with in the slotted portions 23-23 of the plate 21, the recesses 24-24 in the base lock 19 permitting the insertion of the studded heads 30-30. The joint may be disconnected by causing a relative sliding movement between the plate 21 and the friction disc 26, which will result in the disengagement of the studded heads 30-30 from within the slotted portions 23-23 of the plate 21. This type of joint permits the connected member of the body to be swung or moved to its desired position, yet allows the separation of the member from its point of connection to the body.

While I have described in detail the preferred embodiment of my invention, I wish it clearly understood that certain variations therefrom may be resorted to without departing from the true spirit of the present invention and the scope of protection intended to be covered in the present case will appear from the appended claims.

What I desire to cover by the U. S. Letters Patent is

1. The process of producing a display form which consists in forming a positive pattern of an object, covering the positive pattern with a plastic body to produce a negative pattern, separating the negative pattern in sections from the positive pattern, re-assembling the negative pattern sections and progressively lining the negative pattern on its inner surface with strips of pliable material, then removing the negative pattern from the built up strips of pliable material and coating the outside of the built up structure in corresponding colors to the original object.

2. The process of producing a display form which consists in forming a positive pattern of an object, covering the positive pattern with a plastic body to produce a negative pattern, separating the negative pattern in sections from the positive pattern, reassembling the sections and progressively lining the negative pattern with pliable material, then removing the negative pattern and coating the outside of the pliable material with a coloring substance to correspond to the color of the original object.

3. The process of producing a display

- form which consists in forming a negative pattern of the object to be displayed, dividing the negative pattern in sections, then re-assembling and progressively lining the surface of the negative pattern with a pliable material, removing the negative pattern from the built up structure and coating the exposed surface of the structure with a coloring substance.
- 10 4. The process of producing a display form which consists in forming a negative pattern of the object to be displayed, dividing the negative pattern in sections, then re-assembling the sections and progressively lining the surface of the negative pattern with strips of pliable material, removing the negative pattern from the built up structure and coating the exposed surface of the structure with a coloring substance.
- 15 5. The process of producing a display form which consists in forming a positive pattern of an object, covering the positive pattern with a plastic body to produce a negative pattern, separating the negative pattern in sections from the positive pattern, re-assembling the sections and progressively lining the negative pattern on its inner surface with a plurality of superimposed pliable strips, removing the negative pattern from the built up strips of pliable material and finishing the exposed surface of the structure in any appropriate manner.
- 20 6. The process of producing a display form which consists in forming a positive pattern of an object, covering the positive pattern with a plastic body to produce a negative pattern, removing the negative pattern in sections from the positive pattern, then successively reassembling the sections and progressively lining the sections and lapping the joints therebetween with a pliable material and finally removing the negative pattern and coating the exposed surface of the built up structure with a water-proof substance or the like.
- 25 7. The process of producing a display form which consists in forming a positive pattern of an object, forming a negative pattern from the positive pattern, removing the negative pattern in sections and progressively assembling and lining the inner surface of the negative pattern sections with a plurality of strips of pliable material to a sufficient thickness to produce rigidity, then removing the negative pattern and finishing the exposed surface of the pliable material in any appropriate manner.
- 30 8. The process of producing a display form which consists in forming a sectionalized negative pattern of an object to be displayed, successively assembling the sections and progressively lining them and lapping the joints therebetween with a pliable material, then removing the sections and finally finishing the exposed surface of the lining in any appropriate manner.
- 35 In testimony whereof I hereunto affix my signature.

OMAR G. FULLER.
